UNITED STATES PATENT OFFICE.

ELBERT R. TODD, OF DETROIT, MICHIGAN.

DESIGN FOR A SPRAYING-NOZZLE.

SPECIFICATION forming part of Design No. 32,155, dated January 30, 1900.

Application filed January 5, 1900. Serial No. 515. Term of patent 7 years.

To all whom it may concern:

Be it known that I, ELBERT R. TODD, a citizen of the United States, residing at Detroit, in the county of Wayne, State of Michigan, 5 have invented and produced a new and original Design for a Spraying-Nozzle, of which the following is a specification, reference being had to the accompanying drawings, and to the figures of reference marked thereon, o which form a part of this specification.

This invention relates to a new and original design for a spraying-nozzle.

Referring to the drawings, Figure 1 is a perspective view of my new and original design for a nozzle. Fig. 2 is a plan view thereof. 5 Fig. 3 is a side elevation.

The leading or material feature of my design consists of a central conical body surrounded by a concentric ring, standing on a o plane with the horizontal center of said central body, curved arms extending from the base of said body to the under edge of said ring. A gallery tangent to said central body

extends therefrom to the outer edge of said ring.

Referring to the characters of reference, 1 designates the central body, having a central opening 2 at its apex. 3 designates the concentric ring, which is slightly curved, in cross-section. 4 designates the curved arms leading from the base of said body to the under edge of said ring, said arms radiating from the body, as shown. 5 designates the gallery leading from the body to the outer edge of said ring, the whole producing an ornate and 35 harmonious figure.

Having thus fully set forth my invention, what I claim is—

A design for a spraying-nozzle, substantially as herein shown and described. 40

In testimony whereof I sign this specification in the presence of two witnesses.

ELBERT R. TODD.

Witnesses:

E. S. WHEELER,
C. EDNA JOSLIN.
